P. R. NELSON

CIRCUIT CLOSER

Filed May 7, 1927

FIG. 1.

Inventor

Paul R. Nelson

By: *John S. MacLean*
Attorney.

UNITED STATES PATENT OFFICE.

PAUL R. NELSON, OF THE UNITED STATES ARMY, FORT TOTTEN, NEW YORK.

CIRCUIT CLOSER.

Application filed May 7, 1927. Serial No. 189,736.

(GRANTED UNDER THE PROVISIONS OF THE ACT OF MARCH 3, 1883, 22 STAT. L., 625.)

This invention described herein may be used by the Government, or any of its officers or employees in prosecution of work for the Government, or by any other person in the 5 United States, without the payment to me of any royalty thereon.

This invention relates generically to electrical circuit closers and more particularly to the type utilized in the operation of submarine mines.

One object of this invention is to provide a circuit closer which not only establishes a perfect electrical path between its contacting elements but which retains such contact during a sufficient interval to permit the proper functioning of mechanism within the circuit.

A further object is to provide a circuit closer which is of simple and economical construction and efficient and positive in operation.

With these and other objects in view this invention consists in certain novel details of construction, combination and arrangement of parts to be more particularly herein- 25 after set forth and claimed.

Briefly stated, this invention consists in a circuit-closer encased within a suitable housing which is attached to a submarine mine. The circuit closer comprises two electrodes, 30 one of which is stationary and the other relatively movable in respect to the housing, and a spherical contact element which functions to either open or close the circuit by bridging a gap between the electrodes.

Referring more particularly to the accompanying drawings in which corresponding parts are indicated by similar reference characters:

Fig. 1 is a sectional elevation of the circuit-closer showing the position of the contact maker in open and closed position.

In describing the details of construction, which have been adapted for the purpose of illustration, the assembly of the entire mechanism will first be considered.

Referring to Fig. 1 the numeral (1) designates a ball support, which forms one of the electrodes, (2) a ball which functions as a uniting element and (3) a contact plate 50 which forms the opposite electrode. These three parts comprise the circuit making and

breaking elements of the device, which are constructed of suitable conducting materials.

The ball support (1) has an annular external surface (4) with extending peripheries 55 (5). Internally it is provided with a central circular opening (6) which spreads at its upper extremity to form the frusto-section of a cone (7) thereby providing a seat for the ball (2). The top and bottom surfaces (8) and (9) of the ball support (1) are preferably flattened, the bottom surface being provided with a central depending rim (10) which is internally threaded at (11) for the reception of a conductor terminal 60 (not shown). This element is preferably constructed of brass, the internal central opening (6) and the conical surface (7) being nickel plated.

Encasing the ball support (1) is an annular insulating shell (12), preferably made of hard moulded rubber and cast about the ball support (1); so that its interior projects between the extending peripheries (5) on the surface of the ball support. The external surface of the shell (12) is annulated 70 in sections (13), (14) and (15) having stepped diameters, the smallest annular section (15) encasing the depending rim (10) of the ball support (1), the largest section 75 (13) being uppermost and threaded at (16), the upper extremity of its surface. The upper and lower surfaces (17) and (18) of the insulating shell (12) are flattened and parallel to one another and has a central 80 conical opening (19) which aligns with that of the ball support.

A housing (20) is provided to enclose the mechanism and to also form a ground connection for the contact plate (3). This housing is composed of a cylindrical side wall (21) and top (22) and is preferably made of brass and nickel plated although any conducting material of sufficient strength will answer the purpose. The lower portion of the cylindrical wall (21) is internally threaded at (23) to engage the threads (16) of the insulating shell (12), thus forming a 95 waterproof enclosure for the contact mechanism.

Mounted on the upper surface of the insulating shell (12) is a cylindrical spacing 100

ring (24), having flat parallel upper and lower surfaces (25) and (26) and which fits snugly within the cylindrical side wall (21) of the housing (20).

- 5 Reclining on the upper surface (25) of the spacing ring (24) is the metallic contact plate (3), shown in Fig. 2, consisting of a disc which is of smaller diameter than the interior of the housing (20), thereby allowing a clearance which is sufficient to permit the tilting of the same when it is pushed upward by the nickel plated steel ball (2) as will hereinafter be described. In the center of the upper surface (27) of the plate (3) is drilled a hole (28) which does not penetrate the entire thickness thereof and which is of just sufficient diameter to engage the central terminus (29) of a spiral spring (30).
- 20 The lower surface (31) of contact plate (3) is normally held throughout its circumference, against the upper surface (25) of the spacing ring (24) by the spiral spring (30). This spiral spring is interposed between the top 22 of the housing (20) and the contact plate (3) and is normally under a slight compression.

The circuit-closer functions to maintain a break in an electrical circuit located within a submarine mine. As long as the mine remains in an upright position the contact ball (2) remains on its conical seat (7); but when the mine is struck and thereby tilted in any direction by a hostile vessel the ball leaves its seat and rolls outward on the conical surface (7) under the action of gravity.

The ball (2) closes the electrical circuit by wedging itself between the conical surface (7) and the contact plate (3), the latter yielding slightly to the wedging action, as the compression of the spiral spring reacts against the tilting action thereof and retain the ball in contact. The closing of the circuit completes the first event in the cycle which is necessary to the automatic firing of the mine.

The mass of the contact plate (3), the resilience of the spring (30) the mass of the ball (2) and the coefficient of friction between the surfaces all function unitedly to provide the yielding resistance to overcome the impact of the contacting elements. This resistance not only prevents damage to said elements but also prevents the instantaneous rebound caused by the sudden contact thereof, which would be detrimental to the operation of the device, since it is necessary that the circuit remain closed for an appreciable duration of time to allow the proper functioning of the detonating mechanism.

The wiping contact of the steel ball (2) wedging itself against the contact plate (3), as its inertia carries it outward on the conical surface (7), produces a contact which is unfailingly self restoring and non-jam-

ming; so that on return of the mine to a vertical position, the ball will be permitted to return by gravity to its seat.

While my invention is particularly adapted to be applied to electrical circuits for the ignition of submarine mines, it will be readily understood that it may be applied to other apparatus and used for other purposes than herein described, and that the arrangement and structural details of my device may be considerably varied from what has been shown and described without altering the mode of operation of my invention or departing from its spirit and I desire that such modifications shall be included within its scope.

Having described my invention what I claim as new and wish to secure by Letters Patent is:

1. A device of the character described comprising in combination a pair of suitably insulated electrodes normally disposed in a perpendicular position, one of the electrodes being formed with a seat having upwardly and outwardly flared walls, a contact plate situated above and in vertically spaced relation to said seat, said plate being movable rectilinearly along and angularly about its vertical axis, a spherical member of conducting material positioned within said seat, said member when the electrodes are tilted from the perpendicular ascending the inclined walls of its seat into engagement with the plate to establish an electrical path between the electrodes.

2. A device of the character described comprising in combination a pair of suitably insulated electrodes normally disposed in a perpendicular position, one of the electrodes being formed with a seat having upwardly and outwardly flared walls, a contact plate situated above and in vertically spaced relation with respect to said seat, a mounting for the plate permitting movement thereof rectilinearly along and angularly about its vertical axis, said mounting including a compression spring anchored at one end and connected at its free extremity to the center of the plate, a spherical member of conducting material positioned with said seat, said member when the electrodes are tilted from the perpendicular ascending the inclined walls of its seat into engagement with the plate where it is frictionally retained by the latter during a predetermined portion of the period required for the restoration of the electrodes to their normal position.

3. A device of the character described comprising in combination a base of insulating material, a seat of conducting material within the base, said seat having upwardly and outwardly flared inclined walls, a metallic cap mounted on said insulating base, said cap and seat constituting a pair of

electrodes which are normally disposed in a vertical position, a depressible contact plate mounted within the cap in vertically spaced relation with respect to said seat, a spherical member of conducting material located within the seat, said member when the electrodes are tilted from the perpendicular ascending the inclined walls of its seat into engagement with the depressible plate to establish an electrical path between said

electrodes and a compression spring interposed between the plate and the top of said cap and exerting sufficient pressure upon the plate to retain the spherical member in contact with the plate during a predetermined portion of the period required for the restoration of the electrodes to their normal position. 15

PAUL R. NELSON.
